[57] **CLAIM**

The ornamental design for a stackable file tray, as shown and described.

DESCRIPTION

FIG. 1 is a perspective view of a stackable file tray showing my new design;

FIG. 2 is a right side elevational view thereof, the side opposite being substantially a mirror image;

FIG. 3 is a bottom plan view thereof;

FIG. 4 is a top plan view thereof;

FIG. 5 is a rear elevational view thereof; and

FIG. 6 is a front elevational view thereof.
